UNITED STATES PATENT OFFICE

HOMER DAUBENMEYER, OF DETROIT, MICHIGAN

ROTARY PUMP

Application filed May 14, 1928. Serial No. 277,677.

This invention relates to improvements in rotary pumps and provides a simplified construction using a minimum number of parts which are adaptable to quality and quantity 5 production, said parts when rotating require a minimum movement thereby reducing friction, promoting operating efficiency and prolonging the useful life of the mechanism.

Figure 1 is an elevation view of a rotary 10 pump constructed in accordance with my invention.

Figure 2 is an end view with the cover removed showing the rotating members.

Figure 3 is a sectional view taken on the 15 plane indicated by the line 3—3 in Figure 2 as shown by the arrows.

Referring to the drawings wherein like reference characters indicate like parts there is illustrated a housing 1 having an inlet 20 port 6 and an outlet port 7, a projecting hub bored to take the crank shaft 3, a diameter bored to take the rotor 5, a cross hole bored to take the projecting diameter of the oscillator 2, all of which are mounted on a suitable base.

The cover 4 has a projecting hub bored to 25 take the crankshaft 3, a cross hole bored to take the projecting diameter of the oscillator 2, all of which are suitably fastened by screws 8 to housing 1. The crankshaft 3 has a throw 30 one half of the difference in diameters between the housing 1 and the rotor 5 and is mounted free to revolve in housing 1 and cover 4.

The rotor 5 has a hole concentrically bored 35 to take the crankshaft 3 and is free to revolve thereon and a radial slot to take the oscillator 2 with suitable clearance to slide when revolving. The oscillator has two projecting diameters mounted in housing 1 and cover 4 and is free to move like a pendulum 40 and its body extends into rotor 5 thereby separating the inlet from the outlet ports. In operation the crankshaft revolving 45 changes the tangent location of the diameters this movement increases and decreases the volume on either side of the oscillator and produces a rotary pumping action which exhausts 100 percent due to the novel design 50 of the radii of the housing, rotor and oscil-

lator respectively, which function without clearance.

I desire to state that this construction can be varied without departing from the principle of a combined revolving and oscillating movement and this description does not limit in any respect the essentials and principles of this invention.

I claim:

In a rotary pump, the combination of a circular housing, of a crankshaft mounted concentrically through said housing and a radially seated oscillator pivoted tangentially through said housing and forming a dividing wall between inlet and outlet ports, a rotor 60 mounted on said crankshaft free to oscillate, said rotor having a radial slot to receive said oscillator, all of which cooperates in rotation without clearance.
